Primary Examiner — Michelle E. Wilson*Assistant Examiner* — Amanda J Berlinski(74) *Attorney, Agent, or Firm* — Christopher & Weisberg, P.A.(57) **CLAIM**

The ornamental design for a dual element storage container, as shown and described.

DESCRIPTION

FIG. 1 is a front perspective view of a dual element storage container;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in FIGS. 1-3 and 6-7 depict portions of the dual element storage container that form no part of the claimed design.
